(57) **CLAIM**

The ornamental design for a note dispenser, as shown and described.

DESCRIPTION

FIG. 1 is a perspective view showing the new design for a note dispenser;

FIG. 2 is a front view thereof, the rear view being a mirror image thereof;

FIG. 3 is a right side view thereof, the left side view being a mirror image thereof;

FIG. 4 is a top view thereof;

FIG. 5 is a bottom view thereof; and,

FIG. 6 is a perspective view thereof showing the note dispenser with a note.

The portions of the note dispenser in FIGS. 1, 3, 4, and 6 shown in broken lines are included to show features that form no part of the claimed design.
